PAGE 2

FIG. 1 is a front view of an electric organ, showing my new design;

FIG. 2 is an end view of the organ taken from the right side of FIG. 1;

FIG. 3 is a partial sectional view which may be considered as taken in the direction of the arrows substantially along the line 3—3 of FIG. 1; and

FIG. 4 is a perspective view thereof.

The top and back of the organ are plain, and the left side is a reverse complement of the side shown in FIG. 2.

I claim:

The ornamental design for an electric organ, as shown and described.
